ATTORNEY

UNITED STATES PATENT OFFICE.

SEVEREN BELANGER, OF PROVEMONT, MICHIGAN.

RAILROAD TIE.

1,412,648.

Specification of Letters Patent. Patented Apr. 11, 1922.

Application filed July 9, 1921. Serial No. 483,586.

To all whom it may concern:

Be it known that I, SEVEREN BELANGER, a citizen of the United States, residing at Provemont, in the county of Leelanau and 5 State of Michigan, have invented new and useful Improvements in Railroad Ties, of which the following is a specification.

This invention relates to railroad ties, particularly to those of the metallic type, 10 and has for its object the provision of a railroad tie which is formed entirely of metal and which is provided with clamping means whereby to secure the rails upon the tie.

15 An important and more specific object is the provision of a railroad tie having formed upon its top surface flange members adapted to engage over the inner edges of the base portions of rails and formed with 20 longitudinally extending channels within which are movable clamping devices for engaging the outer edges of the rail bases, these clamping members having their inner ends engageable over an upstanding securing 25 member carried by the tie whereby to hold the clamping members in locked position.

Another object is the provision of a tie of this character and rail clamping means 30 which may be readily disengaged whereby the rails may be removed in case of repairs or replacement, the invention further contemplating the provision of a lever tool for moving the clamping members into operative relation to the rails.

35 An additional object is the provision of a device of this character which will be simple and inexpensive in manufacture, highly efficient in use, durable in service, and a general improvement in the art.

With the above and other objects and advantages in view, the invention consists in the details of construction to be hereinafter more fully described and claimed and illustrated in the accompanying drawings in which

Figure 1 is a plan view of my tie showing it in use,

Figure 2 is a longitudinal sectional view 50 therethrough, showing one of the clamping members engaged upon the central member and showing the use of the lever tool for clamping the other rail clamping member,

Figure 3 is a central cross sectional view, 55 Figure 4 is a perspective view of one of the rail clamping members detached.

Figure 5 is a perspective view of the lever tool.

Referring more particularly to the drawings, I have shown my tie as comprising an 60 elongated body 10 formed of metal and provided at the top of its center with a cut-away portion 11 into which leads a longitudinal channel 12 which extends entirely to the ends of the body. Adjacent its ends 65 the top of the body is formed with an up-standing projection 13 and the upper wall of the body is formed with a slot 14 extending from each end to the inner end of the projection 13, this slot 14 leading into the 70 channel 12. Formed integrally upon the top of the body are flanges 15 which are undercut, as shown at 16, for the extension of the inner edges of the bases of the rails A. The rails are to be engaged upon the 75 body by having their bases inserted beneath the flanges 15 and then pressed downwardly so that the bases will lie between the undercut portions 16 of the flanges 15 and the inner edges of the projections 13. It should 80 be stated that the cut-away portion 11 of the body is adapted to be covered by a plate 17 which is detachably secured in position, as by means of bolts or the like.

The body 10 is formed with an upstand- 85 ing projection 18 which is located centrally of its channel 12 and centrally of the cut-away portion 11, as shown, and this projection is formed at its upper end with a round hole 19, and below said hole is formed 90 with a smaller round hole 20. The opposite edges of the projection are formed with ratchet like teeth 21 for a purpose to be described.

In order to secure the rails upon the tie I 95 provide a pair of clamping members for each tie and these clamping members are each formed from a single length of rod of suitable gage. Each clamping member is formed at its outer end with an upwardly 100 extending inclined portion 22 which is engageable over the outer edge of the base of the associated rail. Intermediate its ends each clamping member is formed with one or more convolutions 23 affording more or 105 less resilience whereby to take up undue longitudinal strain. At its inner end each clamping member is bent upon itself to provide an eye 24 at its extremity and also to provide an elongated loop 25 adjacent the 110 eye 24. The loops 25 are designed to be engaged upon the projection 18 so as to hold

the clamping members firmly in such a way that the inclined ends 22 thereof will clampingly engage the outer edges of the rail bases for locking the rails firmly in 5 position.

In the use of my tie it is preferable to employ a lever 26 which has a laterally bent end 27. This lever is inserted through the eye 24 of one clamping member and its lateral end 10 27 is then engaged within either the hole 19 or the hole 20, depending upon the degree of leverage desired. The operator then rocks this lever upon the end 27 as a fulcrum so as to move the clamping member longitudinally 15 to such an extent that the loop 25 may be engaged over the projection 18. Any suitable transverse securing member, such as a pin 28, may then be inserted through the proper one of the holes for preventing the 20 clamping members from becoming disengaged from the projection. The plate 17 is then fastened in position.

From the foregoing description and a study of the drawings it will be apparent 25 that I have thus provided a simply constructed and yet highly efficient railroad tie of the metallic type which will effectively operate to clamp the rails, lever means being provided for applying pressure to the clamping 30 means so as to secure the rails most firmly.

While I have shown and described the preferred embodiment of my invention, it is of course to be understood that I reserve the right to make such changes in the form, construction and arrangement of parts as will not depart from the spirit of the invention or the scope of the subjoined claims.

Having thus described my invention, I claim:

40 1. A railroad tie comprising an elongated body provided at its center with a cut out portion leading to the top and normally covered by a plate, the body being furthermore formed with a longitudinally extending 45 channel and provided with slots at its ends leading into said channel and leading to the top of the body, flange members on the top of the body at points spaced from the ends thereof and beneath which the inner edges 50 of the rail bases may be engaged, an upstanding member within said cut-out portion at the center of the channel, and longitudinally movable clamping members disposed within said channel and formed at their outer ends 55 with portions engageable over the outer edges of the rail bases and provided at their

inner ends with loops engageable over said projection.

2. A railroad tie comprising an elongated body provided at its center with a cut-out portion leading to the top and normally covered by a plate, the body being furthermore formed with a longitudinally extending channel and provided with slots at its ends leading into said channel and leading to the top of the body, flange members on the top of the body at points spaced from the ends thereof and beneath which the inner edges of rail bases may be engaged, an upstanding member within said cut-out portion at the center of the channel, longitudinally movable clamping members disposed within said channel and formed at their outer ends with portions engageable over the outer edges of the rail bases and provided at their inner ends with loops engageable over said projection, the innermost ends of said clamping members being formed with eyes, the projection being formed with holes, and a lever having an angular end insertable through an eye and within one of said holes whereby the clamping member may be pulled longitudinally to engage the loop thereof upon the projection.

3. A railroad tie comprising an elongated body provided at its center with a cut-out portion leading to the top and normally covered by a plate, the body being furthermore formed with a longitudinally extending channel and provided with slots at its ends leading into said channel and leading to the top of the body, flange members on the top of the body at points spaced from the ends thereof and beneath which the inner edges of rail bases may be engaged, an upstanding member within said cut-out portion at the center of the channel, and longitudinally movable clamping members disposed within said channel and formed at their outer ends with portions engageable over the outer edges of the rail bases and provided at their inner ends with loops engageable over said projection, the innermost ends of said clamping members being formed with eyes, and a lever having an angular end insertable through an eye and within one of said holes whereby the clamping members may be pulled longitudinally to engage the loop thereof upon the projection, the edges of the projection being inclined and being formed with ratchet teeth.

In testimony whereof I affix my signature.

SEVEREN BELANGER.
